SUPPORTING BRACKET

Filed Feb. 2, 1927

RALPH PETERSON
INVENTOR

Richard J. Cook
ATTORNEY

UNITED STATES PATENT OFFICE

RALPH PETERSON, OF ELBE, WASHINGTON

SUPPORTING BRACKET

Application filed February 2, 1927. Serial No. 165,404.

This invention relates to improvements in curtain and display supporting brackets and has for its object to provide a device of that character that may be securely fastened to a window casing without the use of nails, screws or other permanent fastenings.

A further object of the invention is to provide a bracket that will serve for the support of a curtain roller and a cross rod for draperies or the like, and which is adjustable to compensate for variations in lengths of such rods and curtain rollers.

Other objects reside in the various details of construction and combination of parts as is hereinafter described.

In accomplishing these and other objects, I have provided the improved details of construction, the preferred forms of which are illustrated in the accompanying drawings, wherein—

Figure 1 is a perspective view showing a bracket embodied by this invention as attached to a window casing.

Figure 2 is a perspective view of the attaching piece for the bracket.

Figure 3 is a perspective view of the bracket member.

Figure 4 is a perspective view of the clamping spring.

Figure 5 is a top view illustrating the disposition of the several pieces where affixed to a window casing.

Figure 6 is a perspective view of a bracket of an alternative construction.

Referring more in detail to the drawings—

The bracket proper comprises a rigid metal strip 1 which is provided, at its outer end, with a vertically extending stud, or pin, 2 and, at its inner end, is bent at a right angle to form a base plate 3; this being provided, at its end, with two inturned points, or teeth, 4. Adjacent the base plate 3, the bracket has an opening 5 therein through which the attaching piece, presently described, may be projected and about midway between the base and outer end is an opening 6 for receiving the supporting pin such as is provided in the end of a roller

curtain. The base plate 3 is also provided with apertures 7 for receiving nails, or screws, in the event that it should be desired to attach it permanently to a casing.

When the bracket is in use, the base portion 3 is disposed flatly against a casing, so that it extends horizontally and vertically edgewise, as shown in Figure 1 and, after being adjusted to proper position, the points 4 are pressed into the casing. An attaching plate 8 is then applied thereto.

The attaching plate comprises a strap 10 adapted to extend through the opening 5 to overlie the base 3 of the bracket, and has its outer end turned inwardly at right angles forming a stop 11 adapted to engage against the side edge of the casing and which has inwardly turned teeth 12 at its end adapted to be pressed into the casing. In the inner end of the attaching piece is a hole 13 adapted to receive a hook end 14 of a clamping spring. The spring comprises a piece of spring wire formed with a loop 16 and two legs 17 and 18. The leg 17 is provided with the hook 14 which seats in the hole 13 of the attaching plate 8 and the leg 18 has a laterally turned hook 19 adapted to engage the inner edge of the window casing so as to produce tension on the spring whereby the plate 8 will be held securely in place.

The brackets are made in pairs for opposite sides of a window and the studs, or pins, 2 serve as a means for holding a rod, as at 24, on which draperies or curtains may be hung and the brackets serve for the support of the roller curtain as indicated at 25.

It is readily apparent that such brackets may be easily attached and may be adjusted along the attaching plate before the points of the base portion are pressed into the casing so as to fit them to curtain rods of different lengths or to compensate for small variations in lengths. They will serve for the support of either the curtain rod or roller, or both together.

In Figure 6 is shown an alternative construction in which the inner end of the bracket body 30 is adapted to seat flatly against the edge of the casing and has teeth 31 inturned therefrom and a lip, or leg, 32

pressed inwardly from the body to overlie the face of the casing. This has a hole 33 for receiving the end of the clamping spring or an attaching screw.

5 Brackets of either type may be made at small cost and in various sizes and in ornamental designs and since various details of construction could be made therein without departing from the spirit of the invention, 10 I do not wish to be limited only to the design herein shown.

Having thus described my invention, what I claim as new therein and desire to secure by Letters-Patent, is:

15 1. A device of the character described comprising a bracket having a laterally extending base portion adapted to seat flatly against a casing and having teeth thereon for projection into the casing and having an opening therethrough adjacent the base, and an attaching plate extending through said opening with its inner portion supportingly overlying the base of the bracket and provided with a hole, and having its outer end turned inwardly to form a stop for engaging the edge of the casing with teeth turned inwardly from said stop for holding engagement with the casing and a spring having one end hooked within the hole in said plate and its other end in holding engagement with the inner edge of the casing.

20 2. A device of the character described comprising a horizontal bracket plate provided at its outer end with a vertical pin for mounting a curtain rod and having an opening for receiving the pivot pin of a curtain roller and having a laterally turned base portion adapted to flatly seat against a casing with teeth turned inwardly therefrom at its end, and having an opening therein adjacent the base plate, an attaching plate extended through said opening with its inner end flatly overlying the base portion of the bracket and its outer end turned inwardly to engage the edge of the casing and having teeth thereon adapted to be embedded in the casing edge, and a tensioning spring detachably fixed to the inner end of said plate and to the inner edge of the casing.

Signed at Everett, Washington, this 18th day of January, 1927.

RALPH PETERSON.
